UNITED STATES PATENT OFFICE.

SAMUEL T. METZ, OF JAMAICA, NEW YORK, ASSIGNOR TO TREO COMPANY, INC., A CORPORATION OF NEW YORK.

UNDERGARMENT.

Application filed May 12, 1925. Serial No. 29,693.

This invention relates to undergarments, and particularly to an improved manner of connecting brassières and girdles to prevent wrinkling of either of the same under the outer garments after bending movements of the wearer. Heretofore, if the brassière and girdle were anchored together along their abutting edges, the wearer could not bend without considerable discomfort, and strain 5 upon the undergarments, and if the brassière and girdle were not connected at the rear and sides, whenever the wearer would bend, the garments would separate along the abutting edges or slide upon one another, and 10 then wrinkle under the outer garments when the wearer returned to erect position.

An object of this invention is to provide an improved undergarment, such as a combination brassière and girdle; which will permit 15 a complete separation from one another of the brassière and girdle sections of the same; which will permit free and substantially unrestrained bending movements of the wearer; which will prevent wrinkling of 20 the undergarment beneath the outer garments when the wearer returns to erect position; which will hold the two sections of the garment in proper relation to one another; which permits ready detachment or 25 attachment together of said sections; with which either section of the garment may be worn without the other; which will not materially alter the appearance of either section of the garment; which will always fit the 30 curvature of the body smoothly; and which will be relatively simple and inexpensive.

Various other objects and advantages will be apparent from the following description of one embodiment of the invention, and the 35 novel features will be particularly pointed out hereinafter in connection with the appended claims.

In the accompanying drawing:—

Fig. 1 is the front perspective of the garment as worn;

Fig. 2 is a rear perspective of the same;

Fig. 3 is a sectional elevation of a portion of the same, with the section taken approximately along the line 3 of Fig. 2; and

Fig. 4 is a sectional plan through the same portion of the garment, with the section taken substantially along the line 4—4 of Fig. 2.

In the illustrated embodiment of the invention, the undergarment comprises the

combination of girdle and brassière sections detachably connected in a particular manner. The girdle section 1 which may be either a closed band or one which may be opened flat, may have elastic sections 2 included therein, 60 if desired. The brassière section 3 may be provided with the usual shoulder straps 4, and extends downwardly in overlapping relation with the girdle section 1, as usual when these garments are worn separately. The 65 brassière section may be provided in front with a strap 5 which may be anchored to a suitable pin in the front of the girdle section as usual. The brassière section may also be formed as a strip of fabric, the ends 70 of which are connected together by suitable fastening devices 6 (See Fig. 2), as usual.

The girdle section is provided with one or more fabric pockets 7 which extend vertically downwardly from approximately the 75 lower edge of the brassière section, said pockets being open at their upper ends. In each pocket a strap 8 of elastic material, such as one having rubber bands incorporated lengthwise therein, is disposed so as to extend lengthwise of the pocket, and at its inner end the strap is anchored to the pocket in any suitable manner such as by stitching or mechanical fastening devices.

The strap terminates at its upper end at 80 approximately the opening of the pocket, and carries a suitable fastening element 9, such as an eye, for cooperation with a suitable fastening device 10, such as a hook, carried by the brassière section along its lower edge 90 (See Fig. 3). The two fastening devices 9 and 10, therefore provide a detachable connection between the lower edge of the brassière section and each elastic strap. The pockets 7 and straps 9 may be provided at 95 the sides or rear of the girdle, preferably both as shown, and the pocket may be readily formed by merely stitching to the girdle a layer 11 of suitable fabric, as shown in Fig. 4.

Preferably two pockets are provided in the rear or back section of the girdle, and optionally may be provided at the sides. The pockets are preferably wider than the straps 8 which are placed therein, so that the free 105 ends of the straps may move laterally in the open ends of the pockets for a limited extent, to facilitate connection of each strap to the lower edge of the brassière section. By means of this limited lateral movement of 110

the strap, the garments may freely adjust themselves to one another and it will be unnecessary to so accurately locate the fastening devices 10 upon the lower edge of the brassière section.

An undergarment constructed in accordance with this invention is worn in the manner shown in Figs. 1 and 2, and when the wearer bends forwardly, the brassière section 10 will move away from the girdle section or slide upwardly along the same, to an extent depending upon the amount of the bending movement. During this bending movement, the straps 8 will stretch or yield and 15 permit this relative sliding movement of the girdle and brassière sections at the rear without offering any material restriction to the bending movements, or causing any discomfort to the wearer.

20 With prior garments when the wearer returned to erect position, the brassière section did not return along its lower edge, but wrinkled, with the result that the wrinkles were frequently visible through the 25 outer clothing and were uncomfortable to the wearer. With this improved garment, however, immediately upon the return of the wearer's body to erect position, the straps 8 will draw the brassière section downwardly 30 into normal position, so as to prevent the forming of wrinkles, and to place the two sections in the same relative positions which they formerly occupied. Such an undergarment will, therefore, always be smooth and 35 flat beneath the outer garments. If the wearer bends sidewise the straps 8 will stretch to permit free movement of the wearer's body, and when the wearer returns to erect position, the straps will draw the 40 garments into their proper normal relation as shown in the drawing.

By providing the straps within pockets in one of the sections, such as in the girdle, especially at the back of the wearer, the 45 straps will always extend along the curving shape of the wearer's body, so that when stretched they will not form vertical ridges in the outer garments. Since the girdle and brassière sections are detachably connected 50 through the straps, they may be readily separated from one another, so that either the brassière section or girdle section may be worn separately without the other, or each 55 may be laundered separately.

It will be understood that various changes in the details, which have been herein described and illustrated for the purpose of explaining the nature of the invention, may be made by those skilled in the art within 60 the principle and scope of the invention, as expressed in the appended claims.

I claim:—

1. An undergarment comprising two body encircling sections, one of which is adapted

to encircle the body of the wearer across the bust, and the other of which is adapted to encircle the body of the wearer at a position downwardly from approximately the waistline, one of said sections having a vertically extending pocket formed therein, an elastic strap disposed in said pocket and anchored at one end to said section with the pocket therein, extending along the pocket, and detachably connected to the other section, whereby said strap will yield when the wearer's body bends in a manner to cause a separation of said sections at the point of connection, and to draw the sections into original relative positions when the wearer's body returns to erect position.

2. An undergarment comprising two body encircling sections, one of which is adapted to encircle the body of the wearer across the bust, and the other of which is adapted to encircle the body of the wearer at a position downwardly from approximately the waistline, one of said sections having a vertically extending pocket formed therein, an elastic strap disposed in said pocket, anchored at one end to said pocket carrying section, extending along said pocket, and detachably connected to the other section, whereby said strap will yield when the wearer's body bends in a manner to cause a separation of said sections at the point of connection, and to draw the sections into original relative positions when the wearer's body returns to erect position, the width of the pocket being greater than the width of the strap whereby the end of the strap which is detachably connected to a section may swing laterally to some extent to facilitate establishment of the connection to a section.

3. An undergarment comprising two body encircling sections, one of which is adapted to encircle the body of the wearer across the bust, and the other of which is adapted to encircle the body of the wearer downwardly from approximately the waistline, the lower section of the garment having a pocket extending vertically of said section for a material distance, the upper end of said pocket being opened and normally lying adjacent the lower edge of the upper section, said pocket being located along the back of the wearer when the garment is in applied position, an elastic strap disposed in said pocket and anchored at one end therein, with the free end of the strap at approximately the opening of the pocket in which it is placed, and cooperating fastening means provided upon the lower edge portion of the upper section and the free end of the strap for detachably connecting the same.

In witness whereof, I hereunto subscribe my signature.

SAMUEL T. METZ.
